UNITED STATES PATENT OFFICE.

CHARLES E. DANIELS, OF ATCHISON, KANSAS.

VALVE-SPRING REMOVING AND REPLACING TOOL.

Application filed October 15, 1925. Serial No. 62,601.

This invention relates to devices or tools for compressing the valve springs of internal-combustion motors for the purpose of removing the valve, and also to assist in 5 replacing the spring when the valve is to be put back in place.

One of the objects of the invention is to provide a tool having a relatively wide range of adjustment thereby permitting of its use 10 in connection with valve springs of motors of various types, and which is easy to operate. In that connection it is also proposed to provide a tool in which all of the parts are accessible thereby facilitating repairs or 15 replacements, and also taking apart thereby to be conveniently placed in a tool kit or box.

A further object of the invention is to provide a quick-acting tool that may be 20 conveniently held in one hand and operated by the other, all of the force due to the compression of the springs being supported by a motor part instead of by the operator. That is to say, it is proposed to provide a 25 tool whose weight, as well as the compressive force of the spring is supported by a motor part while the relative movement of the compressing part of the tool is effected by a lever which is very readily manipulated.

With the above and other objects in view 30 which will more readily appear as the nature of the invention is better understood, the same consists in the novel construction, combination and arrangement of parts hereinafter more fully described, illustrated and 35 claimed.

A preferred and practical embodiment of the present invention is shown in the accompanying drawings, in which:—

40 Fig. 1 is a side elevation illustrating the application of the tool;

Fig. 2 is a horizontal sectional view taken on the line 2—2 of Fig. 1;

45 Fig. 3 is a vertical sectional view taken on the line 3—3 of Fig. 1;

Fig. 4 is a view similar to Fig. 1 showing the manner in which the tool is manipulated to replace the spring preparatory to replacing the valve; and

50 Fig. 5 is a horizontal sectional view taken on the line 5—5 of Fig. 1.

Similar reference characters designate corresponding parts throughout the several figures of the drawings.

55 In its general organization the present tool includes a main compressor frame A

comprising a compressor bar 1 having a handle 2 at its upper end and an angular offset arm 3 at its lower end, while the intermediate portion thereof has the bracket 4 adjustably fitted thereto. The end of this bracket opposite the bar 1 is equipped with the rack bar 5 which is engaged by the holding detent 6 pivotally mounted on the bracket and also by the manipulating lever 7, as will presently more fully appear in detail.

The bracket 4 which may be of the substantially H-shaped formation shown, is provided at one end with the sleeves or guides 4^a for slidably receiving the rack-bar 5 while the opposite end thereof is provided with the guide straps 4^b which slidably embrace the shank of the bar 1. One of the straps may be provided with openings for registering with the openings 1^a in the bar thereby to permit of inserting a fastening 4^c to hold the bracket at any selected point along the length of the bar. The holding detent 6 is pivoted to the bracket as indicated at 6^a and has a handle portion 6^b which is normally pushed away from the frame 4 by the leaf spring 8. This pawl is adapted to engage with the teeth of the rack-bar to hold the bracket in the desired elevated position on the rack-bar, and upon being moved against the tension of the spring 8, it is withdrawn from the teeth of the rack-bar thereby to permit of the bracket descending toward the point or toe of the rack bar.

The manipulating lever 7 is preferably rebent into substantially loop formation and is pivoted to the bracket as indicated at 7^a. The said pivot is located relatively close to the spring tensioned pawl 7^b which engages with the rack teeth to elevate the compressor bar 1 with reference to the rack bar, and as shown in the drawings, the said pawl 7^b may be provided with a thumb or finger manipulating extension 7^c, which may be moved in the direction of the arrow to withdraw the pawl 7^b from the teeth of the rack 5 simultaneously with the withdrawal of the detent 6 to permit the bracket to be lowered or moved toward the point of the rack-bar. This arrangement enables the operator to grasp the bracket in such a way that his fingers may grasp the handle 6^b of pawl 6 while his thumb may operate the lever 7^c to thereby quickly release both pawls from the rack and permit quick re-

moval of the tool to the next valve position.

The looped end of the lever 7 provides a handle H which enables the operator to readily grasp the lever and by relatively 5 slight movement effect the elevation of the compressor bar with reference to the rack-bar when it is resting upon a support.

To assist in positioning the tool on the top of a valve or the like the rack-bar 5 is 10 provided with a handle 5^a, thereby affording ample handhold facilities for positioning and handling the tool during use.

The angular portion 3 of the compressor bar is provided with a fork formed by the 15 spaced members 8—8 which are secured to the arm 3 by the fastenings 9 and cooperate with a resilient washer and spring gripping clip 10 having the spring fingers 11 for fitting over and engaging the washer and 20 lower coil of the spring thereby to hold the same and prevent accidental dropping out when the tool is removed. That is to say, when the tool is removed from its work the spring will stay with the tool until manually 25 detached.

By referring to Fig. 1 the manner of operating the tool to compress and remove the valve spring will be readily apparent.

However, it may be pointed out that after 30 the bracket 4 is adjusted to the desired position on the compressor bar 1 the rack bar 5 is positioned on top of the valve and the bracket is also placed sufficiently low on the rack to obtain necessary travel of the bracket to compress the spring to be removed. With the device arranged and positioned as 35 shown in Fig. 1, the handle H may be moved upwardly in the direction of the arrow in Fig. 1 thereby to move on the pivot 40 7^a and lift the bracket 4 thereby carrying the compressor bar 1 upward. The detent 6 holds the bracket elevated and prevents downward movement and therefore continued reciprocations of the lever 7 will elevate the compressor frame consisting of the bar 1 and the bracket 4 and thereby compress the valve spring due to the fact that the fork 8—8 is engaged beneath the washer which supports the spring. After the 45 cotter-pin which supports the spring washer has been removed, the tool may be moved so that the arm 3 will rock away from the valve stem thereby to release the spring and permit the valve to be removed when the 50 rack 5 is removed from the top thereof.

When it is desired to replace the valve spring before the valve itself is placed back in its seat, the cone plug P shown in Fig. 4, may be utilized for centering and holding the point of the rack bar 5. The manner of replacing the valve spring is illustrated in full lines in Fig. 4, wherein it will be observed that the washer and spring-keeper portion 11 holds the washer against 55 the end of the spring as the lower end of

the latter is moved over into alinement with the upper end which has been slipped over the valve guide of the motor block. After the valve spring has been initially positioned over the valve guide the cone plug 70 P may be removed and the valve put in its seat. The spring may then be compressed while surrounding the valve stem by the manipulation of the lever 7 so that the lower end of the spring will be lifted above the 75 cotter pin hole in the valve stem thereby to permit of the insertion of the cotter-pin.

In connection with the cone plug P it is pointed out that the same is preferably made of brass, copper, or other soft material which 80 will not mar or scratch the valve seat which has been previously ground to provide a proper seat for the valve. This cone acts as a protector for the valve seat during the spring replacing operation. Without the 85 plug it would be difficult to locate a proper place for the point of the rack member 5 to rest on, and furthermore since the tool is made of tool-hardened steel it would be likely to strike the valve seat and dent it or 90 otherwise mar it. Also the relatively conical inner face of the plug makes it possible to manipulate the end of the rack-bar freely in any direction to replace the spring.

Without further description it is thought 95 that the features and advantages of the invention will be readily apparent to those skilled in the art, and it will of course be understood that changes in the form, proportion and minor details of construction 100 may be resorted to, without departing from the spirit of the invention or scope of the appended claims.

I claim:

1. A valve-spring compressing tool comprising a main compressor frame including 105 a compressor bar, a bracket, a plurality of pivoted rack-bar engaging detents carried by said bracket, a rack-bar carried by the bracket, and a lever carried by the bracket and engaging said rack-bar whereby the frame may be moved relative to said rack-bar.

2. A valve-spring compressing tool comprising a main compressor frame including 115 a compressor bar having an offset spring-engaging portion at one end, an offset bracket adjustably engaging with the upper end of the said bar, a rack-bar slidably mounted in the bracket, a detent carried by the bracket adapted to engage said rack-bar, a lever pivoted to the bracket and having a handle extending beyond the compressor bar, and a spring-pressed pawl pivoted at the end of said lever and engaging with the 120 rack.

3. A valve-spring compressor comprising an angular compressor bar having valve-spring engaging means and a handle, a rack-bar disposed parallel to the main shank por- 130

tion of the compressor bar, and a bracket adjustably connecting the compressor bar and rack-bar and vertically adjustable with respect to each of said bars, and means carried by the bracket for moving the compressor bar relative to the rack-bar.

- 5 4. A valve-spring compressor comprising a compressor bar of angular formation having a spring-engaging fork at one end and a handle at the other end, a rack-bar, a bracket of substantially H-shaped formation 10 to provide spaced guides for slidably engaging with the rack and adjustably engaging with the shank of the compressor bar, a rack-engaging detent carried by the bracket, and a lever having a pivoted rack-engaging 15 pawl pivoted to the bracket and having a handle located relatively remote from the pivot.
- 20 5. A valve-spring compressor comprising a main frame consisting of an angular compressor bar having a spring-engaging fork at one end and a handle at the upper end, a bracket connected to the compressor bar 25 adjacent the handle, a rack-bar slidably adjustable in the bracket, means for preventing retrograde movement of the bracket with reference to the rack-bar, and a lever-actuated pivoted pawl carried by the bracket 30 and adapted to elevate the same with reference to the rack-bar.

- 35 6. A valve-spring compressor comprising a main frame including a compressor bar having an offset arm provided with a spring washer-engaging fork portion and also having a handle at its upper end, a bracket ad-

justable on the shank of the compressor bar, a rack slidably guided in the bracket opposite the compressor bar, a detent pivoted on the bracket and including a rack engaging portion and a relatively long handle portion underlying one edge of the bracket, a manipulating lever of loop formation to provide opposite arms pivoted to the bracket and providing a handle extending to one 45 side of the compressor bar, and a pawl pivoted to the ends of the arms of said lever and adapted to engage with said rack.

7. A valve-spring removing and replacing tool comprising in combination, a main 50 frame, a bracket adjustable on the main frame, and a rack adjustable in the bracket, adapted to cooperate with a valve-seat protecting plug having a recess for receiving the end of the rack-bar thereby to assist in 55 replacing the spring in position after the valve has been ground.

8. A valve-spring removing and replacing tool comprising in combination a main frame, a bracket adjustable on the main 60 frame, a rack adjustable in the bracket adapted to cooperate with a valve plug including a stem and a body portion of relatively soft metal, said body portion being of generally conical formation and having 65 a conical recess for receiving the end of the rack-bar thereby to assist in the manipulation of the tool during the spring-replacing operation.

In testimony whereof I hereunto affix my 70 signature.

CHARLES E. DANIELS.
